Primary Examiner — Angela J Lee(74) *Attorney, Agent, or Firm* — K&L Gates LLP(57) **CLAIM**

The ornamental design for a recessed lighting fixture, as shown and described.

DESCRIPTION

FIG. 1 shows a top plan view of a recessed lighting fixture; FIG. 2 shows a top, perspective view thereof; FIG. 3 is a side view thereof; FIG. 4 is another side view thereof; but shown without the broken line structure; FIG. 5 is a top plan view thereof; FIG. 6 is a top, perspective view thereof; and, FIG. 7 is a bottom, perspective view thereof. The broken lines in the drawings show portions of the recessed lighting fixture that form no part of the claimed design.

1 Claim, 7 Drawing Sheets(56)
